UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

STOVE FRAME.

Application filed June 19, 1920. Serial No. 390,058.

To all whom it may concern:

Be it known that I, RUDOLPH HOFFMAN, a citizen of the United States, residing at Kankakee, in the county of Kankakee and State of Illinois, have invented certain new and useful Improvements in Stove Frames, of which the following is a specification.

The invention relates in general to stove construction and has particular reference to the construction of frames employed in the stove structure, the aim of the invention being to provide a frame which may be constructed wholly of sheet metal in a novel and advantageous manner.

15 The principal object of the invention is to provide a frame which may be cheaply manufactured and which presents when completed a neat appearance and is of a very rugged character.

20 The object of the invention thus generally stated, together with other and ancillary advantages, is attained by the construction and arrangement shown in the accompanying drawings forming part hereof, in which

25 Figure 1 is a view in elevation showing my improved frame construction for a stove top. Fig. 2 is a fragmentary under side view on an enlarged scale illustrating the construction of the frame at the forward corners thereof. Fig. 3 is a similar view, but showing the frame construction at the rear corners thereof. Figs. 4 and 5 are respectively sectional views taken on lines 4—4 and 5—5 of Figs. 2 and 3.

35 In carrying out my invention I form the frame from channel bars constructed wholly from sheet metal made in convenient lengths from strips bent along parallel longitudinal lines to provide a base portion or main wall and flange portions or side walls, the flanges being doubled upon themselves to provide a rigid construction. Portions of the main and side walls of the channel bars are cut away to permit of the bending of the bar 40 into rectangular form, and the folded or double character of the channel side walls is utilized in forming rigid joints at the corners of the frame.

45 Referring to Fig. 1 of the drawings, the top frame constituting the present embodiment of the invention comprises a front bar 7 and a rear bar 8 connected together by side bars 9. Preferably the front bar 7 and side bars 9 are formed from one channel strip, and the rear bar 8 is formed from a separate

strip. Between the front bar 7 and the side bars 9 I provide a joint, shown particularly in Fig. 2; and between the side bars 9 and the rear bar 8 a joint, shown particularly in Fig. 3, is employed.

50 Each of the side bars of the frame is of U-shape or channel formation comprising a main or base portion constituting in the present instance the top wall, and edge or flange portions constituting side walls. As shown in Figs. 1 and 2, the main or top wall for the forward and side bars 7 and 9 is designated by the numeral 10 and the side walls of said bars by the numerals 11 and 11^a; and, as shown in Figs. 3 and 5, the top wall 60 of the rear bar 8 is designated by the numeral 12, and 13 and 13^a indicate the side walls of said bar. The outer side walls have inturned portions 14 and the inner side walls have inturned portions 14^a. This construction, while strengthening the bars, readily lends itself to the formation of rigid joints between the side and front and rear bars 65 as will presently appear.

70 The joints between the opposite ends of the front bar 7 and the side bars 9 are formed by cutting away V-shaped portions or notches from the channel strip from which said bars are formed, and also portions of the inner wall of the strip to permit the bending of the strip into rectangular formation with the edge of the notches abutting. Said notches are formed in the top walls of the channels and the inturned portion of the outer side wall of the channel is 75 severed as shown at 11^b in Fig. 2. In cutting the inner wall 11^a of the channel to permit of the bending of the strip, a portion of the inturned fold 14^a is left at one side of the notch so as to provide a tongue 80 85 90 95 11^c (Fig. 2) which is adapted to be bent into engagement with the inturned fold 13^a of the inner wall 13^a of the adjacent side bar when the parts are bent into rectangular form, as shown in Figs. 1 and 2. When the 100 parts are thus bent into the desired form, they are secured together by electric welding, a suitable strip of fusible metal being inserted between the abutting edges of the joint in the top wall of the channel in order 105 that the top walls of the adjoining bars may be effectively secured together in a rigid integral structure. To further strengthen the frame the tongue 11^c is bent into engagement with the inner wall of the 110

adjoining bar and secured to the inner side thereof by welding.

At their ends, the side bars 9 are provided with end walls 10^a adapted to abut the opposite ends of the outer channel wall 13 of the rear bar 8. Said end walls are made from the channel strips by bending the rear end portions of the bases 10 on transverse lines inwardly into the channels (Figs. 1 10 and 3). Preferably the end walls are also made of double thickness providing in-turned portions 10^b. The abutting ends of said portions 10^b and the in-turned portions 14 of the outer channel wall 13^a of the side 15 bars are cut as shown at 14^b (Fig. 3) so as to interfit, and the joint formed is preferably made rigid as by welding.

In forming the joint between the rear ends of the side bars 9 and the rear bar 8, 20 a notch 15 is preferably provided in the top walls 10 of the side bars 9 and the opposite ends of the bar 8 are shaped to provide projecting portions 16 adapted to fit neatly in said notches 15. To secure the side walls 25 of the adjoining bars 8 and 9 together, the in-turned portion 10^a of the channel end wall and the in-turned portion 14^a of the inner side wall, of said bar 9, are cut to provide tongues 17 and 17^a adapted to be entered 30 within the folds of the side walls 13 and 13^a of the rear bar 8 (Figs. 1 and 3) and secured therein as by welding. Preferably also, the joint formed by the notch 15 and projection 35 16 is completed by electric welding, a strip of suitable metal being inserted between the abutting edges of the walls, as in the case of the joints between the front and side bars.

It will be seen that I have produced a 40 frame of relatively simple construction which may be made wholly from sheet metal, so that it may be cheaply manufactured. Moreover, it is of a very rugged character and at the same time presents a neat and 45 finished appearance.

It is to be understood that while the invention is illustrated and described with considerable particularity, it is contemplated that various changes may be made 50 without departing from the spirit and scope of the invention as expressed in the following claims.

I claim as my invention:

1. A stove top comprising a plurality of 55 bars arranged in rectangular form and formed from two strips of sheet metal each bent into channel form, one of said strips providing the front and side bars of the top

and the other one of said strips providing the rear bar of the top, the first-mentioned strip having portions cut away to permit of the bending of the side bars with reference to the front bar, means for securing the front bar and side bars together into a rigid structure, the rear ends of said side bars and the opposite ends of said rear bar being adapted to interengage with the walls of their channels abutting, and means for securing the opposite ends of the rear bar to the rear ends of the side bars, the securing 70 means for the several bars including securing members provided by the side walls of the channels.

2. A stove frame having side members formed of sheet metal of relatively light 75 gauge and bent into channel form with top walls and depending side walls, the top walls of adjoining members being secured together in abutting edge to edge relation by welding, and the side walls being formed from portions of substantial width folded inwardly upon themselves to produce a double thickness with a rounded lower edge, the corresponding side walls of the adjoining members being also rigidly secured together by welding.

3. A stove frame having side members formed of sheet metal of relatively light gauge and bent into channel form with top 80 walls and depending side walls, the top walls of adjoining members being rigidly secured in abutting edge to edge relation by welding, and the side walls being formed from portions of substantial width bent or folded inwardly upon themselves to provide double 85 thickness with rounded lower edges, the corresponding side walls of the adjoining members having overlapping portions welded together to form a rigid joint.

4. A stove frame having side members 100 formed of sheet metal of relatively light gauge and bent into channel form with top walls and depending side walls, the top walls of adjoining members being secured together in abutting edge to edge relation by 105 welding, and the outer side walls being formed from portions of substantial width folded inwardly upon themselves to produce a double thickness with a rounded lower edge, the corresponding side walls of the 110 adjoining members being also rigidly secured together by welding.

In testimony whereof, I have hereunto set my hand.

RUDOLPH HOFFMAN.
